34a Inventor
FIG. 7. Edward H. Remond
326 Edward H. Remond
By Edward R. Alexander
Attorney

UNITED STATES PATENT OFFICE.

EDWARD H. REMDE, OF CLEVELAND, OHIO, ASSIGNOR TO THE BAKER-RAULANG COMPANY, OF CLEVELAND, OHIO, A CORPORATION OF OHIO.

CIRCUIT-BREAKING MECHANISM.

Original application filed December 12, 1921, Serial No. 523,286. Divided and this application filed January 5, 1923. Serial No. 610,791.

This invention relates to a circuit breaking mechanism, wherein an element, which is moved by a motor or otherwise, operates to break the electric circuit to the motor.

5 While the invention is applicable to cut off the power to motors other than of the electric type, I have in the preferred form of the invention disclosed it for the purpose of breaking an electric circuit leading to an

10 electric motor.

In the accompanying drawings, the invention is shown as applied to an elevating platform type of truck wherein the platform is raised by mechanism driven or operated by an electric motor, the cut-out mechanism being connected with the platform and operated thereby when it reaches or approaches its limit of movement in either direction. It will, however, be understood that the invention may be otherwise applied, examples of which are disclosed in my co-pending application Serial No. 513,394, filed November 7, 1921.

One object of the invention is to provide an improved cut-out mechanism of simple construction.

Another object of the invention is to provide an improved cut-out mechanism in which the contact elements cooperate to make and break the circuit relatively quickly.

Other objects of the invention will be apparent to those skilled in the art to which my invention relates from the following description taken in connection with the accompanying drawings.

In the drawings, Fig. 1 is a side elevation (partly broken away) of an elevating platform truck having a cut-out mechanism embodying my invention.

Fig. 2 is a section on the line 2—2 of Figs. 1 and 4, the elements shown being in neutral position.

Fig. 3 is a fragmentary elevation looking at the elements shown in Fig. 2 on the line 3—3 thereof.

Fig. 4 is a section on the line 4—4 of Figs. 2 and 5.

Fig. 5 is a section on the line 5—5 of Fig. 4.

Fig. 6 is a section similar to Fig. 4, but showing the elements in one operated position.

Fig. 7 is a view similar to Fig. 3, but showing the elements in operated positions—one position in full lines and the other position in dotted lines.

Referring to the drawings, 1 indicates as an entirety a truck. 2 indicates the truck frame comprising a section 3, which preferably carries the electric battery or batteries 4, and a section 5, which is relatively low and is adapted to support the elevating platform 6 and, by preference, the mechanism 7 and an electric motor 8 for raising and lowering the said platform. 8^a indicates a lever which operates a controller (not shown) for controlling the electric circuit to the motor 8, to drive it in opposite directions. 9, 10, indicate the pairs of wheels on which the frame 2 is mounted. The wheels 9, 10, or either pair thereof, may be steerable, the operating connections 11, therefor, being actuated by a suitable hand operated device—for example, a lever 12. 13 indicates an electric motor for driving the wheels 9. 14 indicates a lever which operates a controller (suitably mounted in a casing 15) for controlling the electric circuit to the motor 13. 16 is a brake pedal for operating a brake mechanism 16^a. It will be understood that the current for the motors 8 and 13 is supplied by the battery or batteries 4.

17 indicates a link pivoted at 18, to the platform 6 or the raising and lowering mechanism 7 therefor, at one end, and at its opposite end, pivoted at 19 to an arm 20, which forms one element of the limiting means or cut-out mechanism, indicated as an entirety at 21, which is adapted to break the electric circuit to the motor 8 as the platform 6 approaches the end of its movement upwardly or downwardly accordingly as the motor 8 is operated to move it. The arm 20 is pivoted on a stud shaft 22 mounted in an angle plate 23, seated on and secured in any well known way to the L-frame 5^a, which forms a part of the frame section 5. 24 indicates a base plate secured in any suitable manner to the plate 23, as by bolts 25. 26 indicates a cover or casing engaging the plate 24 near its side edges and secured thereto, preferably by the bolts 25 and separate bolts 27.

The casing 26 is arranged to enclose certain of the elements of the cut-out mecha-

nism to be presently referred to. 28 indicates a rock shaft extending through a tubular boss 29, preferably formed integral with the plate 24. The shaft 28 is preferably mounted in a sleeve bearing 30, supported in the boss 29. At its inner end, the rock shaft 28 carries an arm 31, which will be later described. At its outer end, the rock shaft carries a yoke or U-shaped member 32, the legs 32^a, 32^b, of which are disposed upon opposite sides of and in the path of movement of a device 33 projecting laterally from the arm 20. The device 33 preferably comprises a pin or bolt 34 carrying a roller 35 which makes engagement with the legs 32^a, 32^b, and through such engagement serves to swing the yoke (see Fig. 7) and through it to rock the shaft 28 in one direction or the other. The bolt 34 is secured in an opening formed in the arm 20 by a nut 34^a. 32^b indicates inserts preferably formed of steel or other suitable material and secured to the legs 32^a, 32^b, in position to be engaged by the roller 35. In the operation of the arm 20 about its pivot, the roller 35 will engage one of the legs of the yoke 32 and swing it laterally until the adjacent leg is positioned beyond the circular path described by the roller 35, the legs being so disposed and spaced that when either is moved this distance the cut-out mechanism will operate and break the circuit to the motor, in the manner hereinafter set forth. If however, due to inertia of the armature shaft, the platform and other elements connected to it, the arm 20 is carried about its pivot a greater distance than that necessary to operate the cut-out mechanism, the roller 35 will simply ride on the adjacent insert and impart but slight further movement to the rock shaft 28.

36 indicates a spring coiled around the rock shaft 28 or by preference the inner hub portion of the arm 31, as shown in Fig. 2. The opposite ends 36^a, 36^b, of the spring 36 are crossed and disposed on the opposite sides of a pair of lugs 37, 38, disposed one above the other when the arm 31 is in normal position, the former being provided on the inner side of the arm 31 and the latter being provided on the inner face of the base plate 24. As a result of this construction, it will be understood that movement of the arm 31 in either direction will separate the arms 36^a, 36^b, (see Fig. 6) and hence put the spring 36 under tension, and thereby normally exert an influence to return the arm 31 to neutral or mid-position. 39, 39^a, indicate a pair of contacts of suitable construction, mounted on the base plate 24 and connected by leads 39' to proper terminals on the controller (already referred to) for the motor 8, whereby the motor may be stopped and reversed accordingly as the controller is operated either to raise or lower or stop movement of the platform 6. Each of the

contacts 39, 39^a, preferably comprises a pair of spaced plates arranged to receive between them a switch blade 40. 41, 41^a, indicate a pair of stud shafts extending through openings (but insulated from the walls thereof) formed in the base plate 24 and secured therein by nuts 42 engaging the opposite faces of the plate. The shafts 41, 41^a, are connected, preferably on the outer side of the base plate 24, by a plate 41^b, which is provided with a connector 41^c for a feed wire 43. 44, 44^a, indicate levers pivotally mounted on the shafts 41, 41^a. Corresponding arms 44', 44^a', of the levers 44, 44^a, engage cams 45, 45^a, respectively, carried by the free end of the arm 31, while the opposite corresponding arms of the levers engage the switch blades 40 to swing them into and out of engagement with the contact plates of the contacts 39, 39^a, respectively, as will later be set forth. As shown in Figs. 4 and 6, the cams are oppositely disposed so as to swing one of the levers 44, 44^a, about the adjacent shaft when the arm 31 is moved in one direction and to swing the other lever about its shaft when the arm 31 is moved in the opposite direction. The levers 44, 44^a, are provided with lugs 46 and these lugs are preferably connected together by a coiled spring 47 which tends to swing them about their axes in the direction to maintain the lever arms 44, 44^a, in engagement with the cams 45, 45^a. The switch blades 40 are preferably pivotally mounted on the stud shafts 41, 41^a, and are moved thereabout by the adjacent arms of the levers 44, 44^a, each being preferably operatively connected, by devices indicated as an entirety at 48, to the adjacent lever arm in a manner which permits a snap action in making and breaking the circuits through the contacts 39, 39^a. Of the devices 48, 49 indicates a member integrally connected to the hub of the adjacent lever 44, or 44^a, and depending therefrom at one side of the adjacent switch blade 40, 50, 51, indicate a pair of lugs projecting laterally from the member 49 across the path of movement the adjacent switch blade 40 and spaced from each other a distance greater than the width of said blade. 52 indicates a spring, one end 53 thereof being bent or hooked around the outer side of the blade 40 and its other end extending around the hub of the lever and disposed behind a lug 54 preferably provided on the arm 46. In operation, the cam 45 will move the lever 44, which in turn will move the member 49 and arm 46, the movement of the former acting to put the spring 52 under tension. As the lever 44 approaches the limit of its upward movement, as it rides the adjacent cam 45, the lug 50 engages the edge of the blade 40 and moves the latter with it. As soon as the blade swings far enough to permit the spring 130

52 to overcome the friction between the blade and the contact plates 39, the spring will operate the blade with a quick movement to the position shown in Fig. 6, against 5 the lug 51.

Fig. 4 shows the elements of the cut-out mechanism in mid-position and arranged to transmit current to the terminals on the motor to drive it in one direction or the 10 other accordingly as the operating device 8^a is operated to raise or lower the platform. Fig. 1 shows the platform moving upwardly and nearing its extreme upper position.

In approaching this position, the roller 35 15 on the arm 20 engages the leg 32^b and swings it to the position shown in full lines in Fig. 7, thereby swinging the arm 31 laterally and breaking the circuit through the switch blade 40 and contacts 39, as shown in Fig. 6, 20 thus stopping the motor. If the platform 6 moves downwardly, the link 17 will move the arm 20 in the opposite direction and as the platform 6 approaches the limit of its downward movement, the arm 20 through 25 the roller 35 will swing the yoke 32 to the position shown in dotted lines in Fig. 7, thereby swinging the arm 31 and breaking the circuit through the switch blade 40 and contacts 39^a, thus stopping the motor.

30 It will be noted that arm 31 carries two cams 45, 45^a, so disposed and arranged that only one lever is operated when the arm 31 swings laterally in either direction. Accordingly, the breaking of one circuit to stop 35 the operation of motor 8 in one direction, does not affect the other circuit for operating the motor in the opposite direction.

It will also be noted that after one circuit 40 has been broken to stop the motor 8 and following the operation of the motor in the opposite direction and movement of the platform 6 accordingly, the arm 20 will move toward its mid-position. As the arm 20 so moves, the spring 36 will act on the arm 31 45 and swing it and the yoke 32 to normal position. The arm 31 will in turn permit the adjacent lever 44 or 44^a to swing backwardly and such lever acting through the lug 51, will move the adjacent switch blade 40 into 50 engagement with the adjacent contacts.

Due to the shape of the cams 45, 45^a, this re-engagement will be effected relatively quick.

The link 17 or its connection with the platform 6 and arm 20, at either or both ends 55 may be made adjustable in order to vary the engagement of the roller 35 with the legs 32^b, 32^a. As shown in Fig. 7 the link 17 is provided at 17^a with screw threads, such screw threaded end fitting a screw threaded 60 opening in a connecting device 17^b, and permitting adjustment for the purpose just referred to.

From the foregoing description it will be seen that I have provided a relatively simple 65 form of construction which is capable of

being readily positioned for connection with and operation by a movable element to automatically stop it when approaching its limit of movement.

The provision of such mechanism on a 70 truck, such as shown herein for illustrative purposes, enables the operative to control the platform with great facility, as he is only called upon to start the motor 8 in either direction, the cut-out mechanism serving to stop the motor at the desired point. 75

To those skilled in the art of making apparatus of the class described, many alterations in construction and widely differing embodiments and applications of my invention will suggest themselves without departing from the spirit and scope thereof. My disclosures and the description herein are purely illustrative and are not intended to be 80 in any sense limiting. 85

This application is a division of my application Serial No. 523,286, filed December 12, 1921.

What I claim is:

1. In apparatus of the class described, 90 the combination of a pair of leads, a normally closed switch interposed in each lead, devices for operating the movable member of each said switch, said devices operating said movable switch member in one direction with a snap action and serving to positively move it in the opposite direction, means between said devices tending to maintain them in normal position, and means common to said operating devices for both 95 switches and arranged to actuate the devices for either switch. 100

2. In apparatus of the class described, the combination of a pair of leads, a switch interposed in each lead, devices for operating 105 the movable member of each said switch, said devices operating said movable switch member in one direction with a snap action and serving to positively move it in the opposite direction, means common to said operating 110 devices for actuating them, and means tending to return said actuating means to normal position.

3. An apparatus as claimed in claim 1 in which said actuating means comprises an arm 115 swingable relative to said devices and cams on said arm each arranged to actuate the devices for operating one movable switch member independently of the other movable switch member. 120

4. In apparatus of the class described, the combination of a support, a rock shaft mounted thereon, an arm carried by said rock shaft, a pair of stud shafts mounted on said support and connected to a source of 125 current supply, a pair of contacts, sets of switch devices each having a contact member pivotally mounted on one of said stud shafts and arranged to engage and disengage one of said contacts, devices movably 130

mounted on said stud shafts and each operatively connected with one of said contact members, means for operating said rock shaft, and means carried by said arm for operating either of said devices.

5. An apparatus as claimed in claim 4, in which the means for operating said devices is arranged to move either one thereof without affecting the other device.

10. 6. In apparatus of the class described, the combination of a support, an arm pivoted on said support, a pair of stud shafts mounted on said support and connected to a source of current supply, a pair of contacts, sets of 15 switch devices mounted on said stud shafts each comprising a contact member arranged to engage and disengage one of said contacts, a lever and a spring between said lever and contact member arranged to be put under 20 tension and cause relatively quick movement of the latter, means for operating said arm, and means carried by said arm for operating either of said levers.

7. In apparatus of the class described, the 25 combination of a pair of relatively movable members, a circuit making and breaking mechanism carried by one of said members, said mechanism including switch devices through which the circuits for the driving 30 means are completed to cause relative movement between members in opposite directions and an element for operating said switch devices, a connection between said other member and said operating element, 35 whereby one of said switch devices is operated when relative movement between said members is effected in either direction, and a spring arranged to be put under tension when said operating element is moved.

40. 8. In apparatus of the class described, the combination of a pair of leads for electric circuits, a make and break mechanism interposed in each said lead and normally closed to complete the circuit therethrough, each 45 said mechanism comprising a stationary contact and a pair of relatively movable members one of which is arranged to engage and disengage said contact, devices between said members for controlling and limiting their 50 relative movement, said devices including a spring which is put under tension by the relative movement of said members to effect snap action of the movable member, and means common to said mechanisms for operating one of them when moved in either 55 direction.

9. In apparatus of the class described, the combination of a pair of leads for electric 60 circuits, a make and break mechanism interposed in each lead, each said mechanism comprising a stationary contact, a pair of relatively movable members one of which is arranged to engage and disengage said stationary contact and devices between said 65 members to control their relative movement,

said devices including a spring which is put under tension by the relative movement of said members to effect snap action of the movable member and means common to said mechanisms and movable in either direction 70 and arranged to engage the other member of the pair of members to effect disengagement of the first mentioned member of the pair from the adjacent contact.

10. In apparatus of the class described, 75 the combination of a pair of leads for electric circuits, a make and break mechanism interposed in each lead, each said mechanism comprising a stationary contact, a pair of members mounted to swing about a common pivot relatively to each other, one of said members being arranged to engage and disengage said stationary contact and devices between said members to control their relative movement, and means common to 80 said mechanisms and movable in either direction and arranged to engage the other member of the pair of members to effect disengagement of the first mentioned member of the pair from the adjacent contact. 90

11. In apparatus of the class described, the combination of a pair of leads for electric circuits, a make and break mechanism interposed in each said lead and normally closed to complete the circuit therethrough, 95 each said mechanism comprising a contact and a pair of relatively movable members one of which is arranged to engage and disengage said contact, devices between said members for controlling and effecting movement of the last mentioned member in opposite directions to effect engagement and disengagement with said contact, means common to said mechanisms for operating the pair of relatively movable members of one thereof in one direction when moved in either direction, and separate means for moving each pair of relatively movable members in the opposite direction. 105

12. An apparatus as claimed in claim 11 110 in which the separate moving means are common to said pairs of relatively movable members.

13. An apparatus of the class described, the combination of a pair of leads for electric 115 circuits, a make and break mechanism interposed in one of said leads, said mechanism comprising a stationary contact and a pair of members mounted to swing about a common pivot relatively to each other, one of said members being arranged to engage and disengage said contact, devices between said members for controlling their relative movement, and means for operating said mechanism when moved in either direction. 120

14. In apparatus of the class described, the combination of a pair of leads for electric circuits, a make and break mechanism interposed in one of said leads and normally closed to complete the circuit therethrough, 125 130

said mechanism comprising a stationary contact, a pair of relatively movable members one of which is arranged to engage and disengage said stationary contact and devices 5 between said members to control their relative movement, said devices including a spring which is put under tension by the relative movement of said members to effect snap action of the movable member, and 10 means for operating said mechanism arranged to engage the other member of the pair of members to effect disengagement of the first mentioned member of the pair from the adjacent contact.

15 15. In apparatus of the class described, the combination of a lead for an electric circuit, a make and break mechanism interposed in said lead, said mechanism com-

prising a stationary contact, a pair of members mounted to swing about a common pivot 20 relatively to each other, one of said members being arranged to engage and disengage said stationary contact and devices between said members to control their relative movement, said devices including a spring which 25 is put under tension by the relative movement of said members to effect snap action of the movable member, and means for operating said mechanism arranged to engage the other member of the pair of members to 30 effect disengagement of the first mentioned member of the pair from the adjacent contact.

In testimony whereof, I have hereunto subscribed my name.

EDWARD H. REMDE.
